CLAIM

The ornamental design for a footwear heel, as shown and described.

DESCRIPTION

FIG. 1 is a perspective view of a footwear heel, in use in a footwear environment;

FIG. 2 is a front view of a footwear heel, shown without a footwear environment;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is an exploded perspective view of the footwear heel of FIG. 1.

The even length broken lines in the figure drawings are included to show portions of the article and the footwear environment that form no part of the claimed design. The dot-dash broken lines are used to enclose the partial detail views and form no part of the claimed design.
